UNITED STATES PATENT OFFICE.

WEIR B. GILMER, OF SAVANNAH, GEORGIA.

DESIGN FOR AN ELECTRIC STOVE.

54,738.

Specification for Design.

Patented Mar. 23, 1920.

Application filed August 6, 1919. Serial No. 315,765. Term of patent 7 years.

To all whom it may concern:

Be it known that I, WEIR B. GILMER, a citizen of the United States, residing at Savannah, in the county of Chatham and State of Georgia, have invented a new, original, and ornamental Design for Electric Stoves, of which the following is a specification, reference being had to the accompanying drawings, forming part thereof, and in which—

Figure 1 is a top plan view;

Fig. 2 is a bottom plan view;

Fig. 3 is an elevational view of one side;
Fig. 4 is an elevational view of the opposite side;

Fig. 5 is an elevational view of one end; and

Fig. 6 is an elevational view of the opposite end.

I claim:—

The ornamental design for an electric stove, as shown.

WEIR B. GILMER.
